H. Plumb,

Gage Lathe.

No 19,711.

Patented Mar. 23, 1858.

UNITED STATES PATENT OFFICE.

HIRAM PLUMB, OF HONESDALE, PENNSYLVANIA.

MACHINE FOR TURNING TOOL-HANDLES, &c.

Specification of Letters Patent No. 19,711, dated March 23, 1858.

To all whom it may concern:

Be it known that I, HIRAM PLUMB, of Honesdale, in the county of Wayne and State of Pennsylvania, have invented a new 5 and Improved Machine for Turning Tool-Handles and Similar Articles; and I do hereby declare that the following is a full, clear, and exact description of the same, reference being had to the annexed drawings, making a part of this specification, in 10 which—

Figure 1, is a side view of my improvement. Fig. 2, is a transverse vertical section of ditto, taken in the line (x') (x') 15 Fig. 3. Fig. 3, is a plan or top view of ditto. Fig. 4, is a longitudinal section of a portion of ditto, taken in the line (y), (y), Fig. 3. Fig. 5, is a transverse vertical section of ditto, taken in the line (x), (x), 20 Fig. 3.

Similar letters of reference indicate corresponding parts in the several figures.

This invention consists in the employment or use of a series of cutters combined 25 and arranged with a pattern and stops as hereinafter described, whereby a series of the desired articles may be turned and cut successively from a bolt or stick in an expeditious and perfect manner.

30 To enable those skilled in the art to fully understand and construct my invention I will proceed to describe it.

A, A, represent two parallel bars which are connected at their ends by cross pieces 35 (a) (a) and form the bed B, of the machine, said bed being supported at a suitable height in any proper manner.

At one end of the bed B a head C, is attached, said head having a mandrel D, fitted 40 within it, on which a driving and idle pulley (b) (c) are placed. The inner end of the mandrel D, has a chuck (d) attached to receive one end of a bolt or stick E, from which the articles are to be turned.

45 F, is a carriage which is fitted on the bed B, and allowed to slide freely thereon. This carriage has a cord G, attached to it, the cord passing over a pulley H, in the bed and having a weight I, attached to its lower 50 end.

To the inner side of the carriage F, a socket J, is attached. This socket is internally of taper form and a slot or opening (e) is made longitudinally in it at one side to 55 receive the cutting edge of a roughing off tool K, which is attached to a plate (f) se-

cured to the inner side of the carriage F. See Figs. 1, 3 and 5.

L, is a bar one end of which is jointed to one side of the carriage F, as shown at (g). 60 This bar L, has a cutter M, attached to it at about its center. This cutter M, is of gouge shape, and it acts upon the bolt or stick E, directly after the roughing off tool K. The end of the bar L, opposite to the 65 end which is jointed to the carriage has a pendent arm N, attached, and this arm rests on a pattern O, which is secured to one side of the bed B, and forms a series of longitudinal profiles of the articles to be turned. 70 See more particularly Fig. 1.

P, is a bar or plate one end of which is jointed to the carriage F, at the same side where the bar L is jointed. This bar P, has a cutter Q, attached to its outer end, said 75 cutter being what is technically termed a finisher and corresponding with the desired form of the articles to be turned. See Fig. 4.

The outer end of the cutter or finishing 80 tool Q is formed in such a way as to cut off the articles from the bolt or stick as they are finished. This is effected by having a shoulder (h) formed on the end of the tool Q, so as to operate like a chisel and having a 85 fleam (i) attached to a bar (j) which is attached to the bar or plate P, so as to be parallel with the tool Q and directly in front of it, the fleam (i) being in line with the outer edge of the chisel (h), but projecting 90 rather below it so as to cut in advance of the chisel and lighten the work of the same and also enable it to cut off the finished articles smoothly so that their ends will have 95 a finished appearance. The operation of the chisel and fleam will be clearly understood by referring to Fig. 4.

To one side of the bed B, a shaft R is attached. This shaft is fitted in suitable bearings (j'), (j'), and has a handle S, attached 100 to it. A series of stops (k) are also attached to the shaft R at equal distances apart corresponding to the desired length of the article to be turned. A lever T, is attached to the carriage F, at (l) and a pendent pin 105 (m) is attached to said lever. To the outer end of the bar L, a weight (o) is attached.

The operation is as follows: The bolt or stick E, which is of square form the bolts or sticks being thus sawed out from proper stuff, is fitted at one end of the chuck (d) and the opposite end is fitted in the taper 110

socket J. Motion is given the mandrel D, and the bolt or stick E, is rotated, the roughing off tool K, rounding the bolt or stick and allowing it to pass through the 5 socket, the weight I drawing the carriage along on the bed as fast as the bolt or stick is rounded by said tool. The cutter M, as the stick passes through the socket cuts the articles in proper shape owing to the pattern Q, and weight (o), and when a sufficient length of the bolt or stick to form an 10 article has passed through the socket J, the carriage F, is stopped by a stop (k) on the shaft R. The operator then depresses the bar or plate P, by means of the lever T, and the finishing tool Q, completes the work, 15 smoothing the same, while the chisel (h) and flemam (i) cut the article from the bolt or stick. The shaft R, is then turned so that the carriage will be released from the 20 stop (k), that impeded it, and the weight I, draws the carriage along, while a second

article or handle is being cut and so on, the stops (k) arresting the motion of the carriage at the proper intervals so that the 25 articles may be finished and cut off by the finishing tool Q.

I do not claim broadly and irrespective of the arrangement herein shown the employment or use of a pattern in connection with 30 cutters attached to a carriage for such device has been previously used for the purpose of turning various articles, but

Having thus described my invention, what I claim as new and desire to secure by Letters Patent, is—

The roughing off cutter K, socket J, forming cutter M, pattern O, finishing cutter Q, and stops k, combined and arranged to operate as and for the purpose herein set forth. 40

HIRAM PLUMB.
